UNITED STATES PATENT OFFICE.

PETER PAYETTE, OF PENETANGUISHENE, ONTARIO, CANADA.

SAW-MILL DOG.

SPECIFICATION forming part of Letters Patent No. 424,347, dated March 25, 1890.

Application filed June 7, 1889. Serial No. 313,477. (No model.)

To all whom it may concern:

Be it known that I, PETER PAYETTE, manufacturer, of the town of Penetanguishene, in the county of Simcoe, in the Province of Ontario, Canada, have invented an Improved Saw-Mill Dog, of which the following is a specification.

The object of the invention is to provide a mill-dog which is compact in form and adapted for use with logs of large or small diameter, as well as for holding the last board after the log has been sawed up.

Figure 1 is a perspective view of my improved mill-dog. Fig. 2 is a detail of the sliding head-block which carries the dog for the log as well as the dog for the board.

Like letters indicate similar parts in the different figures.

In Fig. 1, A is the base, which may be fastened rigidly in a suitable position, and B is a standard formed thereon, provided with grooved guide-pieces C, one on each side of the sliding piece D, grooved throughout their length, as at a, so as to form a T-shaped slot 25 designed to receive flanges on the vertically-adjustable sliding piece D, whereby the sliding piece D may be moved up and down, as hereinafter described. To the top of the sliding piece D is pivoted at b the arm F, which 30 is also pivoted at its lower end, which is preferably forked, to the bent lever G, as shown. This lever G has a pivot-fulcrum r on the sides and near the base of the standard. On the base A is formed the spring-bearing piece 35 H, formed, preferably, of flat pieces of steel bolted to a block or projection, as shown, and designed to receive in its free end the sliding piece D, so as to avoid any jar should the sliding piece D be permitted to fall through its 40 ways. To the face of the sliding piece D is bolted or otherwise attached the upright I, designed to receive and hold in position the sliding block J, and having holes c to receive the end of the spring-pin K, which passes 45 through bearings d, formed on the upper part of the sliding block J. On this sliding block J is pivoted the log-dog L, the two arms l l' thereof forming an obtuse angle, the shorter arm l being bent, as shown, at the end to form 50 a tooth or spike end w, so as to enter or grip a log at the proper angle. The dotted lines show the log-dog in position to enter a log, the arm

l' being longer and heavier than the arm l, and being also designed to be fitted with a handle. The dotted lines indicate the position of the log-dog L when free to move on its pivot. The arm l' is provided with a pin m, designed to catch under and be held by the curved spring N when the long end l' of the log-dog L is thrown up, so as to be out of the way when not in use, as illustrated in solid lines in Fig. 1. On the sliding block J is formed the catch or lug o, designed to stay the log-dog L in position when the tooth has gripped a log. The sliding block J has also a recess p formed therein, within which and behind the log-dog L is pivoted the board-dog O, the recess p being of sufficient width to allow of a certain play for the board-dog O, of ordinary shape, as shown, and which is provided with a spike end 70 adapted to grip and hold in position the wood while the last boards are being sawed. The other end is held by the bottom t of the recess.

In Fig. 2 there is a back view of the sliding block J, shown with grooved pieces formed thereon to embrace and to hold the sliding block J on the upright I, and being capable of vertical adjustment on the upright I by means of the spring-pin K catching in the holes in the upright. In Fig. 2 is also shown 80 the pin m on the long arm of the log-dog L, caught under the curved spring N.

When it is required to dog a log or piece of square timber, the arm of the log-dog L is freed from the curved spring N and falls 85 into the position shown in dotted lines. By raising the end of the bent lever, G the sliding piece D, which carries the sliding block J and the log-dog L and the board-dog O, can be elevated to the required distance 90 and then be allowed to fall or be jammed down on the log or square timber. The sliding block is made adjustable vertically on the upright I by means of the spring-pin K and holes c in the upright I, so as to adapt 95 the position of the dogs to any size of log or board.

When the board-dog O is only required for use, the pin on the arm of the log-dog is thrown under the curved spring and the log-dog L is out of the way, as shown in the full lines in Fig. 1.

What I claim as my invention is—

1. In a mill-dog, the combination of a base-

piece A and a standard B, having guide-pieces C formed thereon, adapted to receive and hold in position a sliding piece D, with or without a spring-bearing H for the bottom of said sliding piece, an arm F, pivoted to the upper end of the sliding piece D, as well as to a lever G, which has a pivoted fulcrum r near the base of the standard B, an upright I, having holes c formed therein to receive the end of a spring-pin K, located in the upper part of a sliding block J, vertically adjustable on said upright I, a curved spring N, attached at one end to the sliding block J, designed to press on a pin m on the inner face of one of the arms of the log-dog L when it is not in use, a log-dog L, pivoted to said sliding block J, the log-dog L having arms forming an obtuse angle and provided with a bent spike end w, a lug or catch o, formed on the lower portion of said sliding block, a recess p, formed in said sliding block, in which is pivoted a board-dog O behind the log-dog L, and having a bearing t against the bottom of the recess, substantially as described and specified.

25 2. In a mill-dog, the combination of a vertically-adjustable sliding block J, adapted to move along with a reciprocating sliding piece

D, a curved spring N, attached to the sliding block J, a log-dog L, pivoted on said sliding block and having a pin m, designed to engage 30 with said curved spring N, and a catch or lug o, formed on said sliding block, substantially as described and specified.

3. In a mill-dog, the combination of a curved spring N, attached to a sliding block J, and a 35 log-dog L, pivoted on the sliding block J and having a pin or projection m, formed thereon, adapted to engage with said curved spring N, substantially as described, and for the purpose specified.

4. In a mill-dog, the combination, with a recessed and vertically-adjustable sliding block J, adapted to move along with a reciprocating sliding piece D, of a log-dog L and board-dog O, pivoted on said sliding block J, the board-dog O being within a recess p on the sliding block J and behind the log-dog L, and the bearings o and t for said dogs, substantially as described and specified.

Penetanguishene, May 25, 1889.

PETER PAYETTE.
